UNITED STATES PATENT OFFICE.

MORRIS COLKER, OF PITTSBURGH, PENNSYLVANIA.

DESIGN FOR A DISPLAY STAND FOR JEWELRY.

Application filed September 18, 1925. Serial No. 14,816. Term of patent 7 years.

To all whom it may concern:

Be it known that I, MORRIS COLKER, a citizen of the United States, residing at Pittsburgh, in the county of Allegheny and State of Pennsylvania, have invented a new, original, and ornamental Design for Display Stand for Jewelry, of which the following is a specification, reference being had to the accompanying drawing, forming part thereof, in which:—

The drawing is a view in perspective of a display stand for jewelry, showing my new design.

I claim:

The ornamental design for a display stand for jewelry, as shown.

MORRIS COLKER.
